UNITED STATES PATENT OFFICE

JOHN S. O'HARE, OF BETHUNE, COLORADO

SCREED SUPPORT

Application filed March 6, 1928. Serial No. 259,403.

This invention relates to improvements in supports for screeds.

In the construction of concrete buildings, it is necessary to provide screeds which are supported from the falsework and held in level position for the purpose of determining the exact thickness of the cement and for enabling the workmen to obtain a level flat surface. In strictly fire proof buildings, where 10 cement floors are employed, it is also necessary to provide nailing strips to which carpets may be attached. These nailing strips are put into place when the floor is poured and must, of course, be properly positioned 15 and leveled, so that they will have their upper surface on the level with the floor surface when the latter has been finished.

It is the object of this invention to produce a simple and substantial support for screeds 20 and for carpet nailing strips that can be readily attached to the strips and which can be driven into the falsework for the purpose of holding the strips in place.

It is the further object of this invention to 25 produce a screed support that can be used with angle iron screeds or with wooden screeds and which can also be readily salvaged and used over again if desired.

It is the further object of this invention to 30 produce a screed support that can be employed in connection with the construction of side walks for the purpose of holding the wooden strips that form the sides of the sidewalk form.

My improved screed support can be most 35 clearly described and will be most readily understood when reference is had to the accompanying drawing in which the preferred embodiment thereof has been illustrated, and 40 in which:

Fig. 1 is a longitudinal section through a floor falsework showing an angle iron screed supported therefrom by means of my improved screed supports;

Fig. 2 is a section taken on line 2—2, Fig. 1; and shows the manner of securing the screed support to the angle iron screed;

Fig. 3 is a perspective view of my screed support and shows a portion of the screed by 50 means of dotted lines;

Fig. 4 is a section through a carpet nailing strip showing my improved screed support attached to it; and

Fig. 5 is a perspective view showing the manner in which my screed supports can be 55 employed in connection with sidewalk constructions.

Numeral 1 indicates the falsework for the support of the concrete floor construction. This falsework is formed in the usual way by 60 means of planks held in place by suitable supports. As my invention has nothing to do with the exact construction of the falsework, this has merely been indicated in a general way. The level of the finished concrete floor 65 has been indicated by dotted line 2 in Fig. 1. For the purpose of enabling the workmen to pour the concrete the necessary thickness and to enable them to form a level surface, it is necessary to provide screeds, one of which has been indicated by reference numeral 3 in Fig. 2. These screeds may be made of angle iron in the manner shown in Fig. 2, or they may be made of a wooden strip 4, like that shown in Fig. 4. As the screeds are employed only 70 during the leveling process and can be removed, they are preferably made of angle iron as this is more rigid than a wooden screed. After the concrete has been poured and properly leveled, and after it has obtained a certain amount of "set", the metal screeds, together with the screed supports can be removed, after which the channels formed by the screed are filled in by a cement mixture. 75

When the screeds are put into place, they are properly aligned in parallel position and in order to facilitate the proper positioning of the screeds, it is necessary that the screed supports which are located at the ends of the 80 screed shall be longer than the intermediate screed supports. In Fig. 1, the end screed supports have been designated by numeral 5, while the intermediate supports have been 85 designated by numeral 6. The difference in the lengths of these screed supports has been indicated by letter "X".

When the supports are to be employed in connection with an angle iron screed, they are 90 constructed in the manner shown in Figs. 2 100

and 3, from which it will be seen that the screed supports are U-shaped and have parallel side members 7 connected by a flattened end member 8. The end member 8 is provided with an opening 9, for the reception of a flat headed stove bolt 10, which extends through an opening in the screed in the manner indicated. The upper end of one of the side members is also flattened and provided with an opening 11 for the reception of the bolt 12. It is apparent that when the supports are secured to the screeds in the manner in Fig. 2, that they will be held rigidly in place.

When the screed supports are to be employed in connection with wooden screeds of the type indicated by numeral 4 in Fig. 4, and by numeral 13, in Fig. 5, the connecting member 8 is provided with two openings 14 through which the securing screws 15 pass. In every case, however, the end supports must be longer than the center supports in order to facilitate the proper alignment of the screeds. It is evident that screeds like that shown in Fig. 4 can be readily removed from the concrete in the same manner as the angle iron screeds, but where member 4 is to be employed as a nailing strip for carpet, it is, of course, left in place so as to be available for this purpose.

In Fig. 5 I have shown my improved screed supports employed in connection with the building of side walks. When a sidewalk is to be laid, it is customary to place two by fours 13 in parallel relation a proper distance apart. These form the sides of the cement blocks and are ordinarily secured to the ground by means of stakes that are driven into the ground along their outer surfaces. If the side pieces 13 are provided with my improved screed supports, 5 and 6, they can be very quickly and easily put into place as the sharp prongs of the supports can readily be forced into the ground. This greatly facilitates the operation of preparing the forms for the sidewalk and also makes it possible to quickly remove the side members 13 for use in other parts of the sidewalk construction.

I want to call particular attention to the fact that my improved screed support is provided with two parallel arms and therefore when it is put into place, it will hold the screed against sidewise motion as well as hold it in a predetermined distance above the false work. Although I have illustrated the supports as having the sides 7 parallel, it is evident that these sides can be spread apart in the manner indicated by dotted lines in Fig. 4. This forms a more rigid support for the screeds but makes it difficult to remove the screeds and screed supports owing to the angular relation of the sides, where the screeds and screed supports are to be removed therefore, it is preferable to have the sides parallel 65 in the manner shown.

I want to call attention to the fact that the connecting portion 8 has been flattened so as to permit the support to be seated more steadily against the screed, and, when the supports are to be employed with an angle iron screed, the upper end of one of the side members is also flattened for the same purpose.

From the above description it will be apparent that I have provided a simple screed support that will greatly facilitate the placing and the removal of screeds such as are used in the construction of concrete floors for fire buildings. I also wish to call attention to the combination shown in Fig. 1 in which the end supports are longer than the intermediate ones, as this greatly facilitates the proper placing of the screeds.

Having described the invention what I claim as new is:

1. In combination, a straight screed, a plurality of supports attached to said screed and spaced apart along one side thereof, the supports nearest the ends of the screeds being longer than the intermediate supports whereby they will come into contact with a flat supporting surface before the intermediate supports thereby facilitating the operation of aligning the screed.

2. A screed support consisting of a substantially U-shaped metal member whose sides are substantially straight and parallel, the ends of the sides being pointed to facilitate their insertion into a supporting surface, the base of said member being formed by a straight portion which is adapted to fit against the under surface of a screed, the upper surface of the base and a portion of one side member being flattened to fit against the sides of an angular screed, said flattened portions each having an opening for the reception of a securing means.

3. A screed for use in connection with the laying of concrete floors and the like comprising, in combination, a straight bar of angle iron having a plurality of supports secured thereto, the supports each comprising, a metal bar bent at two points into a substantially U-shape, the sides being parallel and pointed, the base which connects the sides being straight and flattened so as to fit against one side of the angle, a portion of the side adjacent the end being also flattened and adapted to fit against the other flange of the angle, said flattened end and side being provided with openings adapted to register with corresponding openings in the screed and bolts extending through the openings for securing the supports to the screed.

In testimony whereof I affix my signature.

JOHN S. O'HARE.
